[57] **ABSTRACT**

A reheating furnace for slabs or billets is provided with at least one temperature measuring device having an upwardly directed radiation receiving surface provided by a plate located at the upper end of a cylindrical housing. Substantial thermal insulation is provided around the housing and in use the radiation receiving surface of the plate is disposed closely adjacent to and facing the underside of a slab being heated, the thermal insulation shielding the surface from ambient radiation whereby radiation is received by the surface substantially solely from the under surface of the slab.

SHEET 1 OF 3

FIG. 2.

FIG. 3.

TEMPERATURE MEASUREMENT

To control furnaces for reheating stock such as metal slabs or billets requires a knowledge of the stock temperature. Attempts to do this have met many problems some associated with the very high temperature of gases in the furnace e.g., more than 1,300°C. Proposals to use radiation pyrometers for measuring stock temperature have not been successful because, among other reasons, the radiation from the flames and furnace walls are reflected from the slab surface and slabs are cool relative to the furnace walls at the commencement of heating.

According to the present invention there is provided a furnace for heating metal slabs including means for supporting metal slabs during their movement through the furnace, a plurality of heat sources located within the furnace and at least one temperature measuring device having an upwardly directed radiation receiving surface disposed at a level below the level of the top of the supporting means; said device being so constructed and arranged that in use the radiation receiving surface is disposed closely adjacent and facing the underside of a slab being heated, said surface being substantially shielded from ambient radiation within the furnace whereby radiation is received on said surface substantially solely from the under surface of the slab.

The measuring device according to the invention can be spaced a small distance from the slab so that background radiation is eliminated. The spacing can for example be between 1 and 3 centimetres. By disposing the device so that it faces the underside of the stock, variations in stock size do not affect the spacing of the stock from the device, a problem which has been encountered by many previously proposed devices. Since the surface is close to the slabs any scale which falls on to the surface will be removed as the slabs are pushed along over the surface.

The furnace can be on any type of furnace but is preferably a pusher furnace in which the supporting means consists of skids extending along the length of the furnace supported on cross members. The temperature measuring device can be mounted on a supporting system independent of the skid support system or can be mounted on a cross member that also supports the skids. The device can be rigidly mounted but it is also possible to have the radiation receiving surface movable so that it can be deflected by bent slabs. For example the device can be pivoted and spring urged. There are preferably a number of temperature measuring devices spaced along the length of the furnace. The furnace can be of a type in which all the burners are directed in the same sense or of a type in which the burners in the preheat zone are opposed to the burners in the soak zone.

The temperature measuring device preferably includes a housing, a plate forming said radiation receiving surface thermally insulated from the housing, and a thermocouple connected to the plate, the leads for the thermocouple passing through said housing. Preferably the housing is surrounded by insulating material presenting a generally flat surface generally level with the radiation receiving surface. The leads can pass through the furnace in close proximity with the cross member which may be suitably cooled. One of the advantages of the invention is that no separate holes have

to be provided in the furnace walls for the device to pass through.

In the accompanying drawings:

FIG. 1 shows a longitudinal cross section through one example of a slab reheating furnace with temperature measuring devices in accordance with the invention,

FIG. 2 is a section on the line II — II of FIG. 1 and

FIG. 3 is a cross section through the temperature measuring devices shown in FIGS. 1 and 2.

A slab reheating pusher furnace 2 has two heating zones 4 and 6 with a waste gas offtake 8 between them. The zone 4 is longer than the zone 6 and each zone is heated by burners 10 in the end walls of the zones so that the flames of the burners 10 in zone 4 are opposed to the flames of the burners 10 in zone 6. Water cooled skids 12 extend along the length of the furnace 2 for supporting slabs 14 to be heated. The burners 10 are disposed above and below the skids 12 so that the slabs are heated from below as well as above. The skids 12 are supported on cross members 16 consisting of water cooled pipes which in turn are supported on water cooled upright members 18.

Slabs 14 to be heated are introduced through an entrance 20 and are pushed through the furnace 2 by successively introduced slabs until the slabs are discharged through discharge chute 22.

The skids 12 consist of water cooled pipe 24 supported on which is a rail 27 on which the slabs 14 bear.

A number of temperature measuring devices 26 are spaced along the length of the furnace 2 mounted on cross members 16. Each device 26 includes a cylindrical housing 28 connected to the cross member 16 by a sleeve 30 to which it is welded after the desired height of the device has been determined. The housing 28 is surrounded with thermal insulation 32. At the upper end of the housing 28 there is a plate 34 forming a generally flat radiation receiving surface 36 thermally insulated from the housing 28 by thermally insulating material 38. A thermocouple 40 passes into the plate 34. The plate 34 is held in position by a cylindrical member 48. A lead 50 for the thermocouple, passes through a plug 46 in the member 48 at the bottom end of the housing 28 and passes along the cross member 16. The lead 50 is strapped to the cross member 16 and is covered with thermal insulation 52. The inside of the member 48 is filled with insulating material.

The upper surface 36 of plate 34 is arranged to be spaced between 1 to 3 centimetres below the level of the top of the rails 27 that support the slabs 14 and hence the same distance below the bottom of the slabs 14. The upper surface 42 of the insulation material 32 is level with the surface 36 and offers sufficient blockage such that practically no radiation reaches the surface 36 except radiation from the slabs 14. The thermocouple 40 will therefore register a reading which is related to the temperature of the slabs 14.

The thermal insulation 32 has a generally flat surface 42 generally level with the surface 36. The insulation 32 serves to prevent stray furnace radiation from reaching the surface 36 and to achieve that end it must not be too small. However, as the size of the insulation 32 is increased to provide additional shielding for the measuring device 26, the slabs 14, are in turn, shielded from the furnace heat. This is generally undesirable,

therefore the size of insulation chosen must be a compromise.

We claim:

1. A metal slab reheating furnace, comprising: means for supporting metal slabs during their movement through the furnace; heat sources within the furnace and at least one temperature measuring device comprising a housing having an open upper end; a plate providing an upwardly directed radiation receiving surface disposed in the open upper end of said housing at a level below the level of the top of said supporting means, means disposed between said plate and the open end of said housing; for insulating said plate from said open end and thermal insulation means surrounding the perimeter of said surface, said surface being disposed in use, closely adjacent to and facing the underside of a slab being heated and being substantially shielded from ambient radiation within the furnace by said thermal insulation means whereby radia-

tion is received on said surface substantially solely from the under surface of the slab.

2. A furnace as claimed in claim 1 wherein said thermal insulation means surround the exterior side wall surface of said housing.

3. A furnace as claimed in claim 2 wherein said thermal insulation means is disposed level with said radiation receiving surface of said plate.

4. A furnace as claimed in claim 3 wherein said housing comprises a hollow cylindrical member packed with thermally insulating material.

5. A furnace as claimed in claim 1 wherein a plurality of said heat sources are disposed above and below the supporting means.

6. A furnace as claimed in claim 1 wherein said radiation receiving surface is disposed at a level between 1 and 3 centimetres below the level of the top of the supporting means.
